UNITED STATES PATENT OFFICE

111,224

DESIGN FOR AN ILLUMINABLE MIRROR OR SIMILAR ARTICLE

Oliver C. Ritz-Woller, Chicago, Ill.

Application May 4, 1938, Serial No. 76,982

Term of patent 7 years

To all whom it may concern:

Be it known that I, Oliver C. Ritz-Woller, a citizen of the United States, residing at Chicago, in the county of Cook and State of Illinois, have invented a new, original, and ornamental Design for an Illuminable Mirror or Similar Article, of which the following is a specification, reference being had to the accompanying drawing, forming part thereof.

In the drawing:

Fig. 1 is a front elevational view of an illu-

minable mirror or similar article embodying my new design, the mirror portions being shown at *a, b, c, d* and *e* and the portions for emitting light rays being shown at *f* and *g*;

Fig. 2 is a side elevational view thereof; and

Fig. 3 is a bottom plan view thereof.

I claim:

The ornamental design for an illuminable mirror or similar article, substantially as shown and described.

OLIVER C. RITZ-WOLLER.
